CLAIM

The ornamental design for an electric motor, as shown and described.

DESCRIPTION

FIG. 1 is a front perspective view of a electric motor showing our new design;

FIG. 2 is a front view thereof;

FIG. 3 is a rear view thereof;

FIG. 4 is a right side view thereof;

FIG. 5 is a left side view thereof;

FIG. 6 is a bottom plan view thereof;

FIG. 7 is a top plan view thereof;

FIG. 8 is a rear perspective view thereof;

FIG. 9 is a front perspective view thereof, show in environmental use; and,

FIG. 10 is another front perspective view thereof, shown in environmental use.

The broken lines represent unclaimed subject matter and form no part of the claimed design.
